J. R. DAW

AIRPLANE TOY

Filed Dec. 15, 1922

Patented Mar. 31, 1925.

1,531,849

UNITED STATES PATENT OFFICE.

JOHN R. DAW, OF LINCOLN, NEBRASKA.

AIRPLANE TOY.

Application filed December 15, 1922. Serial No. 607,090.

To all whom it may concern:

Be it known that I, JOHN R. DAW, a citizen of the United States, residing at Lincoln, in the county of Lancaster and State of Nebraska, have invented certain new and useful Improvements in Airplane Toys, of which the following is a specification.

My invention relates to airplane toys particularly of the windmill type with the airplanes moving in a circular path about a vertical axis.

My primary object is to provide an airplane toy which will be attractive and almost irresistible to children as well as to grown-ups.

Another of my objects is to so design the airplane toy that it can be manufactured at the lowest possible cost.

Another of my objects is to provide an airplane device which will spin readily when carried in the hands of a running child or when mounted in a stationary position where there is a light breeze.

Still another of my objects is to provide an airplane device which will make a very striking and attractive ornament for the radiator cap of an automobile.

Having in view these objects and others which will appear in the description, I will now refer to the drawings, in which—

Figure 1 is a view in isometric projection of one form of my airplane toy.

Figure 2 is a top plan view of the device, showing also a dummy propeller which I add to the structure shown in Figure 1 and by way of modification thereof.

Figure 3 is a side elevation of the forward portion only, of the modified form of the airplane toy as shown in Figure 2.

Figure 4 is a detail view of the blank from which the body portion of the airplane is made.

Figure 5 is a view of the tail portion of my airplane toy, showing particularly the cut away portion which serves as a guide for the flapper, the form of tail shown being the same as that shown in Figures 2 and 3.

Figure 6 is a detail view of the flapper.

Figure 7 is a view showing the manner in which the tail part is secured to the planes.

In carrying out my invention, I secure a button 10 to the standard 11 by means of a vertical pivot 12. On the periphery of the button are mounted two or more equidistantly-spaced radiating arms 13. The structure thus far described constitutes a spider

serving as a support for the airplanes, which are secured to the arms 13 at their outer extremities.

The blanks out of which the planes are formed are constructed as shown in Figure 4. An elongated sheet of any suitable material, such as cardboard or sheet metal, is cut in the form shown, with openings at 14 and 15 and with creases or weakened portions at 16. At one end of the blank are tongues 17 which are adapted to be threaded each through a pair of slits 18 after the blank has been folded on the lines 16. The result is a rectangular structure having open ends corresponding to the openings 14 and 15 of the blank. To this box like structure I secure the tail 19, the position of the tail being in transverse median relation with respect to the planes. The securing means are clearly shown in Figure 7 and with reference to Figures 4 and 5. Slits 20 are cut in the tail and through these slits are passed short strips 21 of suitable sheet metal, the strips being folded upon themselves at their middle points. In assembling the device the folded protruding ends of the strips 21 are passed through the slits 22 of the blank shown in Figure 4 and are then upset in opposite directions as shown in Figure 7.

Rotation of the device in the wind is brought about by means of a pivoted flapper which rises into the path of the wind at a certain point in the rotation of the airplane and which falls out of the path of the wind at another point. The construction of the flapper 23 is shown in Figure 6. Near the forward end of the tail in the portion between the planes is a cut-away part leaving an opening 24 in the tail. The opening 24 is in the shape of a sector whose angle is acute and it serves as a guideway for the flapper. The flapper in its two extreme positions abuts against the sides of the opening, but in its lowermost position it does not reach the horizontal, nor does it reach the vertical in its uppermost position. At the bottom edge of the flapper is a notch 25 which rests in the angle of the opening 24 and serves to steady the flapper in its movements. Looped strips 26 are secured to the flapper at its lower extremities, and the blank shown in Figure 4 is provided with pin holes 27. In assembling the parts, the strips 26 will be in alignment with the pin holes 27, after which pins 28 are inserted in the pin holes and into the loops of the

strips 26. The pins 28 will thus serve as pivots for the flapper.

In use, it is necessary to have two or more airplanes secured to the spider as shown.

- 5 At the start all flappers will be in their down position because their weight will normally hold them down. However in the airplane which points in the direction of the wind, the wind will be directed against the under side of the flapper and will cause it to lift upwardly on its pivot. In this position the flapper will be an obstruction to the wind, which causes the airplane to travel through an arc on the pivot 12. When 10 the wind no longer strikes the flapper on its rear surface, the weight of the flapper combined with the pressure of the wind on the forward surface will cause the flapper to assume its down position until it has 15 again assumed the position where the wind strikes it in the rear. It is necessary to have at least two of the airplanes on the spider for the best results. However, while two airplanes alone will give satisfactory results, 20 they occasionally halt for an instant on dead center, and I have found it best to use at least three.

To add to the attractiveness of the device, I may add a pinwheel 29 which serves as a 30 dummy propeller for the airplane. The spider and its pivoted button may of course be varied in any one of several ways. In mounting the airplanes on the arms of the spider, I may tack them onto the upper surface of the arms, or I may split the arms 35 at their ends and slip one of the planes into the slit, where a drop of glue or other adhesive will secure it. This feature is also susceptible of numerous modifications. I 40 have worked out a design whereby the complete article may be placed on the market, or whereby the parts may be packaged, the purchaser being enabled to assemble them easily and quickly.

45 Having thus described my invention and its advantages, what I believe to be new and

desire to secure by Letters Patent of the United States is—

1. An airplane toy comprising a plurality of toy biplanes mounted to rotate about a common center, each of said biplanes including a pair of spaced horizontal planes having therebetween a channel for the passage of air currents, and a pivotally mounted flapper between the planes of each pair, 55 said flapper being so arranged that a current of air from the rear will cause the flapper to swing into position for closing the channel between the pair of planes while a current of air directed against the front 60 of the airplane will cause the flapper to swing into the position for leaving the passage between the planes open and unobstructed.

2. A toy airplane structure comprising 65 an upper and a lower plane connected at their ends, a tail secured to said upper and lower planes and projecting in the rear of said structure, a flapper pivoted to said structure between the upper and lower 70 planes, a guideway in the forward portion of said tail for guiding the movements of said flapper, and a dummy propeller secured to the front end of the tail.

3. An airplane toy comprising a plurality 75 of toy airplanes secured to rotate about a common center, each of said airplanes comprising an upper and a lower plane and means for connecting the planes at their lateral edges and in spaced relation, a tail 80 secured in upright position between said upper and lower planes and projecting in the rear of said planes, said tail having in its forward portion an aperture in the form of a sector whose apex is at the forward 85 end and at the lowermost part of said aperture, and a flapper pivoted to swing between the sides of said aperture and about the apex of said aperture as a center.

In testimony whereof I affix my signature.

JOHN R. DAW.
